(57) **CLAIM**

The ornamental design for an electrical power unit, as shown and described.

DESCRIPTION

FIG. 1 is a front perspective view of an electrical power unit showing our new design in an open-cover configuration, viewed from above and to the right;

FIG. 2 is a rear perspective view thereof, viewed from above and to the left;

FIG. 3 is a top plan view thereof;

FIG. 4 is a front elevation thereof;

FIG. 5 is a rear elevation thereof;

FIG. 6 is a left side elevation thereof; and,

FIG. 7 is a right side elevation thereof.

In the drawings, the broken lines depict unclaimed subject matter only and form no part of the claimed design. A bottom view forms no part of the claimed design.

1 Claim, 3 Drawing Sheets
